United States Patent Office

Des. 202,289

Patented Sept. 14, 1965

202,289

DOOR FOR VENDING MACHINES OR THE LIKE

Harry Greenwald, New York, N.Y., assignor of one-third
each to Louis Wolff and Harry Silberglaib, both of
Brooklyn, N.Y.

Filed Nov. 18, 1964, Ser. No. 82,675

Term of patent 14 years

(Cl. D52—3)

FIG.1

FIG.2

FIG.3

FIG.4

FIG. 1 is a front elevational view of a door for vending machines or the like, showing my new design;

FIG. 2 is a side elevational view thereof;

FIG. 3 is a top plan view thereof; and

FIG. 4 is a rear elevational view thereof.

I claim:

The ornamental design for a door for vending machines or the like, substantially as shown.
